(57) **CLAIM**

The ornamental design for a spineless, reversible, fully encasing book cover, as shown and described.

DESCRIPTION

FIG. 1 is a perspective view of the book cover of my new design from the front right thereof;

FIG. 2 is a front view thereof;

FIG. 3 is a rear view thereof;

FIG. 4 is a right elevational view thereof;

FIG. 5 is a left elevational view thereof;

FIG. 6 is a bottom perspective view thereof;

FIG. 7 is a top perspective view thereof;

FIG. 8 is a perspective view thereof from the front right, showing the flap portion in a partially open position;

FIG. 9 is a perspective view thereof from the rear right, showing the top part of the flap portion inverted towards the top and front;

FIG. 10 is a perspective view thereof from the front right, showing the lower part of the flap portion pulled towards the front;

FIG. 11 is a perspective view thereof from the front right with the bottom portion of the body partially pushed in upward;

FIG. 12 is a perspective view thereof from the rear right with the bottom portion completely pushed in upward; and,

FIG. 13 is a perspective view thereof from the rear right with the book cover completely reversed.
